[57] CLAIM

The ornamental design for a belt mounted clip for police night stick or the like, substantially as shown and described.

DESCRIPTION

FIG. 1 is a perspective view of the belt mounted clip for police night stick or the like showing my new design; the broken line showing of a strap is for convenience of illustration and forms no part of the claimed design; FIG. 2 is a top plan view thereof; FIG. 3 is a right side elevational view thereof; FIG. 4 is a left side elevational view thereof; FIG. 5 is a front elevational view thereof; and FIG. 6 is a rear elevational view thereof.

FIG. 2

FIG. 4

FIG. 6
